UNITED STATES PATENT OFFICE.

WEBB C. BALL, OF CLEVELAND, OHIO.

DESIGN FOR A SPOON, &c.

SPECIFICATION forming part of Design No. 20,845, dated June 23, 1891.

Application filed May 4, 1891. Serial No. 391,571. Term of patent 14 years.

To all whom it may concern:

Be it known that I, WEBB C. BALL, a citizen of the United States, residing at Cleveland, in the county of Cuyahoga and State of Ohio, have invented and produced a new and useful Design for the Handle of a Souvenir Spoon, Fork, or Knife, of which the following is a specification, reference being had to the accompanying drawings, forming a part thereof.

Said drawings represent the two faces of a spoon-handle, and, as the same handle design is intended to apply to a fork or a knife handle, it is not thought necessary or required to duplicate the drawings for those special articles.

My design comprises the handle of a spoon, fork, or knife having the following characteristics: Surmounting the end of the handle is a figure of the American eagle. Below the eagle and near the end of the handle, upon its face side, is a space in which is to appear the medallion of some eminent American—as Washington, Lincoln, Grant, Sherman, or Garfield—in relief. This medallion-space is surrounded and embellished by scroll-work, substantially as shown. En-

twined around the handle is the American flag, the staff of which is shown substantially parallel with the handle. If desired, the colors of the flag may be shown in enamels; but in this respect my design is not essentially limited, as the stars and stripes may be made to appear in any way. Upon the back of the handle, under the eagle, is an engraving-space shaped in the form of a shield, upon which a giver's or receiver's name, or a date, or the name of a place may be engraved. Upon the face of the spoon-bowl or upon the fork-body or knife-blade may be shown stars, substantially as illustrated.

This design, as will be seen, is intended to be of a national and patriotic character.

What I claim is—

The design for spoons herein shown and described.

In testimony whereof I sign this specification, in the presence of two witnesses, this 11th day of April, 1891.

WEBB C. BALL.
